PAPER FEEDING MACHINE

Fred W. Barkley, Winthrop, Mass.

Application February 12, 1930, Serial No. 427,830
Renewed April 24, 1934

69 Claims. (Cl. 271—38)

The present invention relates to paper feeding machines which separate individual sheets from a pile and deliver them in succession to a mechanism or machine for operating thereon.

5 The principal object of the invention is to produce a sheet separating and delivering machine which will operate at high speed in a reliable and certain manner to separate sheets from a pile and deliver them in regular succession to 10 a folder or other machine for operating upon the sheets and which will replenish the pile, from which the sheets are separated and delivered, automatically.

To the accomplishment of this object, and such 15 others as may hereinafter appear, the features of the invention relate to certain methods, devices, combinations and arrangements of parts hereinafter described and then set forth broadly and in detail in the appended claims which 20 possess advantages readily apparent to those skilled in the art.

The various features of the present invention will be readily understood from an inspection of the accompanying drawings illustrating the best 25 form of the invention at present known to the inventor, in which,

Figure 1 is a view in right side elevation of the sheet feeding machine;

Fig. 2 is a detail view in front elevation, partly 30 in section, of the mechanism for separating the uppermost sheet from the pile;

Fig. 3 is a view in plan, the upper inclined feeding table and the two feeding bands being removed to show underlying parts;

Fig. 4 is a detail view in rear end elevation, partly in section;

Fig. 5 is a detail plan, partly in section, of the mechanism for delivering the separated sheet from the pile;

Fig. 6 is a detail view in right side elevation, partly in sectional elevation, on the line 6—6, Fig. 5;

Fig. 7 is a diagrammatic view of the upper and lower supply tables and the reversing throat 45 therebetween;

Fig. 8 is a detail view in plan of the lower supply table;

Fig. 9 is a detail view in sectional elevation on the line 9—9, Fig. 8.

50 Fig. 10 is a detail view in sectional elevation on the line 10—10, Fig. 9;

Fig. 11 is a detail view in front sectional elevation of the sheet delivering drum;

55 Figs. 12, 13 and 14 are diagrammatic views illustrating progressive positions of the uppermost

sheet in the pile during its movement of separation from the pile;

Fig. 15 is a detail view in plan of the caliper and ejecting mechanism;

Fig. 16 is a view in right side elevation of the 5 parts shown in Fig. 15;

Fig. 17 is a detail view in front sectional elevation on the line 17—17, Fig. 16;

Fig. 18 is a detail view in right side elevation, partly in section, of the caliper and ejecting 10 mechanism;

Fig. 19 is a view in rear sectional elevation on the line 19—19, Fig. 18;

Fig. 20 is a view showing a diagram of the 15 magnet and resistance coil circuits connecting the sheet separating mechanism and the bank feeding clutch-actuating mechanism;

Fig. 21 is a detail showing a modified form of the winding device for elevating the top sheet 20 from the pile;

Fig. 22 is a detail view in underside plan of 25 another modified form of the winding device for elevating the top sheet from the pile;

Fig. 23 is a detail view in elevation of the device shown in Fig. 22;

Fig. 24 is a detail view in plan of the valve 30 mechanism in the air exhausting system, and

Fig. 25 is a detail view in right side elevation, partly broken away and partly in section, of the valve mechanism.

Referring first to Fig. 1 for a preliminary general description of the machine and the work performed thereby, the sheets are stacked in a pile on a table shown at the extreme left of the figure. The sheets are withdrawn one at a time 35 from the pile on the table and delivered to a machine or mechanism for performing a subsequent operation upon the sheets. The diminishing pile on the table is replenished by an automatic mechanism which feeds the front end of a 40

bank over the table beneath a staking finger. During the feed of the front end of the bank on the table the staking finger drags over the exposed face of the uppermost sheet in the pile until the staking finger rides off the leading edge 45

of the sheet and engages the exposed face of the next to the top sheet in the pile. When this occurs the leading edge of the top sheet in the pile is engaged by a hold-down. The uppermost sheet in the pile is withdrawn from beneath the hold- 50

down by a rotary suction roll rotating constantly about a fixed axis in a clock-wise direction and having substantially the same construction and mode of operation as the rotary suction roll disclosed in my application filed December 10, 1929, 55

Serial No. 413,023. This roll engages the exposed face of the uppermost sheet adjacent its trailing edge and withdraws it entirely by suction from beneath the hold-down. As the sheet is drawn from beneath the hold-down the trailing edge of the sheet engages fingers which are moved to operate an electric circuit, containing a magnet to open the conduit, through which air is drawn from the roll to the atmosphere, thus to reduce the suctionsal effect of the roll on the sheet. Under reduced suction the roll tends to hold the trailing edge of the sheet in contact with the fingers without moving the sheet. When the leading edge of the sheet is withdrawn from beneath the hold-down, the leading edge of the separated sheet snaps upwardly, or is elevated by a winding device, into position for the operation of a suction drum which rotates constantly about a fixed axis in a contra-clock-wise direction, and having a somewhat similar mode of operation as the rotary suction drum disclosed in my application hereinbefore referred to. This drum snatches the separated sheet from the roll and delivers it entirely by suction from the pile. During its delivery from the pile the sheet is picked up bodily from the pile and is wrapped partially about the periphery of the drum so that the sheet leaves the drum in a direction reverse to that in which the sheet moves when the drum snatches the separated sheet from the separating roll. Automatic mechanism is provided for caliperizing the sheet as it leaves the drum. This caliperizing mechanism controls an ejecting mechanism. When a single sheet leaves the delivering drum the ejecting mechanism is not responsive to any movement of the caliperizing mechanism. When, however, two or more sheets become stuck together and are delivered by the drum from the pile as a unit the caliperizing mechanism detects the presence of the plurality of stuck-together sheets and throws the ejecting mechanism into operation to eject said plurality of sheets out of the path in which the individual sheets are conducted to the folder or other mechanism. The automatic mechanism for replenishing the pile of sheets operated upon by the separating roll and the delivering drum comprises an upper supply table, a reversing throat, a lower supply table, a band for feeding a bank, formed by hand stacking, over the supply table, and a band for feeding the bank over the lower supply table to the pile supporting table. The mechanism for operating the feeding bands is under the control of the same fingers which control the suctionsal pull on the separating roll so that the feed of the bank is stopped when the trailing edge of the separated sheet engages said fingers. The feed of the bank is restarted when the delivery drum snatches the separated sheet from the separating roll. The feeding bands normally engage each other forming a reversing throat. The lower supply table feeding band is mounted to yield and allow the bank to force the bands apart so that the reversing throat automatically adapts itself to the thickness of the bank. The front and rear ends of the under supply table float on springs which impel the table upwardly towards fixed abutments. The vertical position of the under supply table thus depends upon the thickness of the bank fed thereover.

In the illustrated embodiment of the invention a bank 21 (Fig. 1) is formed by hand stacking feathered or fanned out sheets upon an upper inclined supply table 22. The bank 21 is fed from the table 22 through a reversing throat 23

to a lower supply table 24 inclined reversely from the supply table 22. The bank is fed on the upper supply table 22 towards the rear of the machine and the bank 21 is fed on the lower supply table 24 towards the front of the machine which for the purposes of the present disclosure is considered as that portion of the machine adjacent the mechanism to which the sheets are fed for a subsequent operation. The sheets placed on the upper supply table 22 are feathered or fanned out so that the bevel on the end of the bank, directed towards the rear end of the machine, is exposed. That is, each sheet, in said portion of the bank, except the uppermost sheet underlaps the sheet above it from the bottom to the top of the bank. When the beveled end of the bank is reversed and then fed over the under supply table 24 each sheet in said end, except the lowermost sheet, overlaps the sheet below it from the top to the bottom of the bank.

One end of the supply table 22 is supported from the machine or mechanism to which the sheets are fed. The other end of the table 22 is supported by brackets 25 supported in turn from a horizontal rod 26 the opposite ends of which are secured, respectively, to vertical brackets 27 (Figs. 1, 3 and 4) and 28 (Fig. 3). The brackets 27 and 28 are secured, respectively, to side-frames 29 and 30 each of which is supported from the floor by a column 31 (Figs. 1 and 3). The bank 21 is fed down the supply table 22 by a continuous band 32 the upper run of which passes around a drum 33 (Figs. 1, 3 and 4) on a shaft 34 the opposite ends of which are journaled, respectively, in the brackets 27 and 28 (Fig. 3). The lower run of the band 32 passes over a drum 35 (Figs. 1 and 3) which is mounted to rotate loosely on the rod 26 between fixed collars 36 thereon.

Outside the bracket 27 (Fig. 4) the shaft 34 is provided with a gear 37 which meshes with a gear 38 mounted to rotate loosely on a horizontal stud 39 secured at one end to the bracket 27. Loosely mounted on the stud 39 is a worm wheel 40 which is driven by a worm 41 on a vertical shaft 42, one end of which is journaled in a bracket 43 carried by the side-frame 29 and the other end of which is carried by a bracket 430 on the side-frame 29. Beneath the bracket 430 the vertical shaft 42 is provided with a bevel gear 44 which meshes with a larger bevel gear 45 on a stub-shaft 46 one end of which is journaled in a bracket 430. The bracket 430 is mounted in the side-frame 29 so that it may swing about the axis of the shaft 46 for a purpose presently to be described. The other end of the stub-shaft 46 is journaled in a bracket 47 supported from the side-frame 29. The bevel gear 45 is driven by a smaller bevel gear 48 (Fig. 1) provided with a hub 49 secured to a shaft 50 (Fig. 4) one end of which is journaled in an arm 51 of a yoke 52 carried by a bracket 53 on the side-frame 29. The other end of the shaft 50 is journaled in the other arm 54 of the yoke 52. Pinned to the shaft 50 is the hub 55 of one member 56 of a clutch the other member 57 of which is formed on a sleeve 58 splined to the hub of a pulley 59 loosely mounted on the shaft 50. As the hub of the pulley engages the face of the clutch member 56 and as the pulley engages the bearing 54 the pulley is held from movement longitudinally of the shaft 50. The clutch members 56 and 57 are normally held in engagement by a spring 60 coiled around the hub of the pulley 59 and interposed between the sleeve 58 and the pulley. The pulley 59 is driven by a belt 61 from some suitable source of power through a variable transmission (not

shown). In addition to this variable transmission the rate at which the bank 21 may be fed over the supply table 22 may be varied by changing the gear ratio between the gears 37 and 38 both of which are mounted for ready removal on the ends of the shafts 34 and 39, respectively, as shown in Figs. 1 and 4.

Through the connections described the drum 33 is driven in a clock-wise direction (Fig. 1) to feed the bank 21 along the table 22 to the reversing throat 23. This throat 23 is the space between the band 32 and a second band 62 which engages the upper surface of the table 24 and feeds the bank 21 thereover. As shown in Fig. 7 the bands 32 and 62 engage when no bank is passing through the throat 23. As the bank, formed on the table 22, builds up in thickness the band 62 is moved away from the band 32 by the bank to form a throat 23 corresponding in width to the thickness of the bank. The bank also pushes the under supply table 24 downwardly to permit the bank to pass in between the table 24 and the roll 33.

The under supply table 24 (Fig. 8) comprises inclined side bars 63 and 64 which are connected at their rear ends by a horizontal rod 65. At their front ends the bars 63 and 64 are connected, respectively, to arms 66 and 67 projecting rearwardly from hubs 68 and 69 in which a horizontal shaft 70 is journaled. As shown in Fig. 1 the side-frame 29 is cut-away. The side-frame 30 is similarly cut away to allow the shaft 70 to move vertically in a manner presently to be described.

The bank 21 is supported upon the table 24 by a central board 71 and two side slats 72 and 73. As shown in Figs. 8 and 9 the rear ends of the board 71 and side slats 72 and 73 are supported by the rod 65. To this end the board and slats are provided with depending blocks 74 (Fig. 9) having a groove 75 therein which engages the upper surface of the rod 65. The block 74 carries a leaf spring 76 which engages the lower surface of the rod 75. With this construction the rear end of the board and slats, while supported in a rigid manner, may be slid readily along the rod 65 to space them apart different distances laterally.

Near its front end the board 71 rests upon two arms 77 and 78 (Fig. 10) which are carried respectively by the rear ends of curved straps 79 and 80 secured together by a tie-rod 81. The front ends of the straps 79 and 80 are each provided with a yoked end 82 the arms of which embrace the lower portion of the shaft 70. The connected straps 79 and 80 are supported for lateral adjustment upon a horizontal rod 820 the opposite ends of which are supported in blocks 821 and 822 depending from the arms 66 and 67, respectively. The lateral adjustment of the straps 79 and 80 on the rod 820 is maintained by a set screw 823 (Fig. 9). Intermediate their ends the board 71 and straps 72 and 73 are supported for lateral adjustment by blocks 74 and springs 76 on a tie-rod 83 connected to the side-bars 63 and 64.

The opposite ends of the rod 65 are pivotally connected, respectively, to the lower ends of links 84 and 85 (Fig. 3) the upper ends of which are connected, respectively, to the free ends of arms 86 and 87 projecting from hubs 88 and 89 on a rock-shaft 90 the opposite ends of which are journaled in the brackets 27 and 28. The arm 85 is maintained normally in an elevated position by a coiled spring 91 (Fig. 1), which is coiled about a rod 92 pivoted on an arm 93 projecting rear-

wardly from the side-frame 29, and interposed between a collar 94 on the rod 92 and a plate 95 secured in a pivotal manner to the arm 86 through which plate the rod 92 extends loosely. The arm 87 is maintained normally in an elevated position by a spring 96 (Fig. 3) connected from the side-frame 30 and the arm 87 like the spring 91 for the arm 86. With this construction the rear ends of table 24 are impelled vertically by means of the springs 91 and 96 to maintain the rear end of the table 24 engaged normally with an abutment comprising the band covered roll 33. The springs 91 and 96 also maintain the band 62 pressed against the band 32 to close the reversing throat 23.

The opposite ends of the shaft 70 (Fig. 8) are supported in hubs 97 and 98 (Fig. 10) which are connected, respectively, by links 99 and 100 to the long arms of bell-crank levers 101 and 102. The lever 101 (Fig. 1) is pivoted at 103 upon the side-frame 29. The short arm of the bell-crank lever 101 is connected to a rod 104 which passes loosely through a block 105 pivoted on the side-frame 29. Coiled about the rod 104 and interposed between the block 105 and a washer 106 on the rod is a spring 107. The adjustment of the spring 107 may be regulated by a collar 108 adjustably secured to the rod. The bell-crank lever 102 is connected to the side-frame 30 through a spring 107 (not shown) in a manner similar to the bell-crank lever 101 so that the opposite ends of the shaft 70 are supported yielding to maintain normally the front end of the table 24 engaged with an abutment comprising two rolls 109 (Figs. 1, 5 and 6), presently to be described.

In order to drive the band 62 and thus feed the bank along the table 24, the shaft 70 carries a roll 110 (Figs. 8, 9 and 10) over which the upper run of the band 62 passes. The roll 110 is splined to the shaft 70 and rotates between the yokes 82 (Fig. 8) so that when the board 71 is adjusted laterally, the board 71 and roll 110 move together as a unit. The lower run of the band 62 passes over a roll 111 (Fig. 9) the opposite ends of which are journaled in the arms 66 and 67, respectively, (Fig. 8). From the roll 111 the lower run of the band 62 passes under a roll 112 (Fig. 1) journaled in the lower end of a frame comprising two straps 113 and 114 (Fig. 10) tied together by tie-rods 115 and 116 (Fig. 1). The free ends of the straps 113 and 114 are pivoted on the rod 820. With this construction the roll 112 bears on the band under the influence of gravity and thus constitutes a gravity take-up for the band 62. From the roll 112 the band 62 passes over a roll 117 (Figs. 1 and 3) mounted to rotate freely on the shaft 90 between the hubs 88 and 89. From the roll 117 the band 62 passes over a roll 118 mounted to rotate between the collars 119 and 120 on a rod 121 having its opposite ends secured, respectively, to the brackets 27 and 28. From the roll 118 the band 62 passes under the roll 33 in contact with the band 32. The band 62 also contacts with the board 71 throughout its length. The rolls 33, 117, 118 have extended surfaces to permit the shifting of the band 62 laterally thereon.

In order to rotate the shaft 70 and thus move the band 62 over the board 71 to feed the bank thereon, the right-hand end of the shaft 70 carries a worm-wheel 122 (Figs. 1 and 3) which is driven by a worm 123 on an inclined shaft 124. One end of the shaft 124 is supported in the arms 125 and 126 of a double-yoke 127 the arms 128 and 129 of which are supported by the shaft 70 with the worm-wheel 122 mounted between them. The other end of the shaft 124 is journaled in the

swinging bracket 130, Figs. 1 and 4. The shaft 124 is driven from the bevel gear 45 by a bevel gear 131, on one end of the shaft 124, in mesh with the gear 45.

5 With this construction the bands 32 and 62 are driven in time relation from the bevel gear 45 to feed the bank down the upper supply table 22 and through the throat 23 and over the lower supply table 24. When no bank is being fed 10 through the reversing throat 23 the band 62 contacts with the band 32 as they pass underneath the roll 33 due to the action of the springs 91 and 96 which press the rear end of the table 24 upwardly. At the same time the front end of the 15 table 24 engages the rolls 109 due to the action of the springs 107 which press the front end of the table 24 upwardly.

When the bank 21 is formed on the upper supply table 22 and then fed to the reversing throat 20 23 the underlapping edges of the fanned out sheets in the bank gradually wedge the band 62 away from the band 32 until the reversing throat 23 is opened to accommodate the full thickness of the bank. During the passage of the bank through 25 the reversing throat 23 onto the table 24 the bank pushes the band 62 from the full line position of Fig. 7 to the construction line position therein. During this movement of the band 62 the rock-shaft 90 rocks in a counter clock-wise direction and the arms 86 and 87 move downwardly against the tension of the springs 91 and 96. Because the roll 112 and its frame are mounted 30 to swing freely upon the rod 820 the roll 112 acts as an automatic belt tightener or gravity take-up to maintain the band 62 taut as the band 35 62 moves away from the band 32.

After the front end of the bank passes through the throat 23 the travelling band 62 feeds it over the table 24 towards the front end thereof. 40 When the overlapping edges of the fanned out sheets in the bank reach the front end of the table 24 they enter between the roll 110 and the opposed abutment rolls 109 and gradually wedge the roll 110 and the front end of the table 24 45 downwardly against the tension of the springs 107 as shown by comparison of the full and construction line positions of Fig. 7.

The front end of the bank after it passes through the space between the band feeding roll 50 110 and the abutment rolls 109 curves downwardly until it engages a pair of spaced rails 132 (Figs. 1, 7 and 14) the rear ends of which are supported by a cross-piece 133 (Fig. 1) carried by brackets 134 and on the side-frames 29 and 30. 55 The front ends of the rails 132 are supported from the machine or mechanism to which the sheets are fed. Associated with the rails 132 are slats 135 and 136 (Fig. 3). The rails 132 and the slats 135 and 136 are mounted for lateral 60 movement similarly to the board 71 and the slats 72 and 73 of the table 24. The front end of the bank is pushed over the rails 132 and the slats 135 and 136 by that portion of the bank being fed over the table 24 by the band 62. The 65 rails 132 and the associated slats 135 and 136 constitute a supporting table 137 for a pile of superimposed sheets comprising the front portion of the bank 21. The sheets piled on the table 137 are withdrawn one at a time by mechanism to be described. Notwithstanding this 70 constant reduction in the pile it is replenished constantly by other sheets contained in the front end of the continuous bank.

As shown in Figs. 12, 13 and 14 a bend is 75 imparted to the bank in that portion which bridges

the gap between the tables 24 and 137. In order to vary the location and extent of this bend both the band feeding roll 110 and the abutment rolls 109 are adjustably mounted so that their relative positions may be changed to accommodate the machine to different kinds of paper and different conditions of use. That is, the axes of the band feeding roll 110 and the abutment rolls 109 may be arranged in a vertical plane or in inclined planes extending downwardly either forwardly or backwardly with reference to the front of the machine. Moreover, the axis of the roll 110 may swing downwardly against the tension of the springs 107 in an arc extending forwardly or backwardly with reference to the front of the machine. In this swinging movement of the roll 110 the bracket 130 swings about the axis of the shaft 46.

To this end the hubs 97 and 98 (Figs. 3 and 10) on the shaft 70 are provided, respectively, with 20 arms 140 and 141 to which are connected links 142 and 143. As shown in Fig. 1 the link 142 is pivotally secured by a nut 144 to an arm 145. One end of the arm is pivoted at 146 to the side-frame 29. The other end of the arm 145 is connected to the side-frame 29 by a bolt 147 and a nut 148. The shank of the bolt is mounted in an arcuate slot 149 formed in the side-frame 29. By loosening the nut 148 the position of the bolt 147 in the slot 149 may be changed to swing the 30 arm 145 about its pivot 146 and thus vary the angle of the plane in which the axes of the rolls 109 and 110 extend. This adjustment is maintained during the operation of the machine by tightening the nut 148. The arm 145 is provided with a series of holes 150 (Fig. 1) so that the pivotal point of connection between the link 143 and the arm 145 may be changed to vary the manner in which the roll 110 swings under the depressing influence of the bank as it passes 40 between the roll 110 and the abutment rolls 109. The link 143 is adjustably connected to the side-frame 30 in a manner similar to the connection of the link 142 to the side-frame 29.

The abutment rolls 109 are adjustable vertically and also about a fixed axis. To this end the left-hand roll 109 (Figs. 5 and 6) is mounted to rotate freely in a yoke 151 projecting forwardly and downwardly from the lower end of a slide 152 mounted to slide vertically in ways 153 formed in the vertical face of a support 154. The slide 152 may be held in any position of vertical adjustment on the support 154 by a bolt 155 threaded into the support and mounted to pass through a slot 156 in the slide 152. To facilitate the adjustment of the left-hand roll 109 vertically the upper end of the slide 152 is engaged by the end of a bolt 157 which is threaded through an opening 158 (Fig. 5) formed in a cap 159 bolted to the horizontal face of the support 154. The right-hand roll 109 is mounted to rotate freely in a yoke 159 (Fig. 5) projecting forwardly and downwardly from the lower end of a slide 160 (Fig. 1) which is adjustably mounted on the vertical face of the support 154 in a manner similar to the slide 152 for the left-hand roll 109.

The support 154 is mounted for lateral adjustment upon two horizontal spaced bars 161 and 162 (Figs. 1 and 6). To this end the support 154 has a portion 163 formed to slide between and in engagement with the bars 161 and 162. The support 154 is provided with a bolt 164 which passes through the portion 163 and is threaded to receive a nut 165 the head of which engages 75

the bars 161 and 162 to clamp the support 154 in any position of lateral adjustment on the bars. The ends of the bars 161 and 162 are supported, respectively, by arms 168 and 167 (Fig. 3) projecting from hubs 168 and 169 loosely mounted on a horizontal shaft 170. The ends of the shaft 170 are journaled in brackets 171 and 172 on the side-frames 29 and 30, respectively. The hubs 168 and 169 are rotatably adjustable about the shaft 170. To this end the hubs 168 and 169 each carry bolts 173 and 174 (Fig. 1) which pass through arcuate slots 175 and 176 in the brackets 171 and 172, respectively. With this construction the hubs 168 and 169 may be rotated about the axis of the shaft 170 and then secured in their position of adjustment by nuts 177 and 178 (Fig. 11) on the bolts 173 and 174.

Mounted between the abutment rolls 109 in position to engage the uppermost sheet in the bank is a staking finger 179 (Figs. 5, 6, 12, 13 and 14). This staking finger is thin (Fig. 6), and has a wide end (Fig. 5) engaged with the exposed face of the uppermost sheet. The staking finger 179 at its rear end is secured by a screw 180 to the horizontal arm of a bell-crank lever 181 pivoted on a horizontal pin 182 carried by the lower end of a vertical plate 183 (Fig. 5). The plate 183 is bolted to the vertical face of the support 154 so that the staking finger 179 is moved when the support 154 is adjusted laterally on the bars 161 and 162 or is adjusted about the axis of the shaft 170. In order to press the wide end of the staking finger yieldingly against the exposed face of the uppermost sheet in the bank the plate 183 houses a coiled spring 184 arranged to engage a cup 185 formed in the free end of the vertical arm of the bell-crank lever 181. The tension of the spring 184 may be adjusted by an adjusting screw 186 carried by the plate 183 and arranged to engage a plunger 187 engaged with the spring 184. The forward position of the wide end of the staking finger 179 may be varied. To this end the staking finger is slotted to embrace the shank of the screw 180 and its rear end is turned upwardly to fit in a groove 188 on an adjusting screw 189 threaded into a cylindrical opening formed in the bell-crank lever 181.

The staking finger 179 is flanked (Fig. 5) on either side by guard fingers 190 and 191 formed on one end of a plate 192 which is mounted for adjustment upon the staking finger. To this end the plate 192 is slotted to embrace a bolt having a head 193 engaged with the plate 192 and an adjusting nut 194 engaged with the hold-down 179. The fingers 190 and 191 constitute a hold-down for holding the top sheet in the pile after its leading edge moves from beneath the staking finger 179.

Referring now to Fig. 1 the front portion of the bank has been fed from the upper inclined table 22, over the lower inclined table 24 and onto the table 137 where it forms a pile. During the pushing of the front end of the bank over the table 137 the exposed face of the uppermost sheet in the bank rides under the staking finger 179 until finger 179 reaches a position adjacent the leading edge of the uppermost sheet in the pile (Fig. 12). The leading edge of the sheet is the one in advance when the sheet is delivered from the machine. The trailing edge is the one opposite the leading edge. During the continued feed of the front end of the bank over the table 137 the staking finger rides off the top sheet and engages the exposed face of

the next to the top sheet in the pile (Fig. 13). The principal function of the staking finger 179 is to prevent any movement of the sheets in the pile on the table 137 other than through the feed of the front end of the bank thereon. The top sheet in the pile is now held on the table 137 by the hold-down comprising the fingers 190 and 191 in position for the operation of the device which separates the uppermost sheet in the pile and the device for withdrawing the separated sheet from the pile.

The devices for separating the sheets in the pile and withdrawing them one at a time from the pile, comprise a rotary suction roll or drum 195 (Figs. 1 and 3) and a rotary suction roll or drum 196 (Figs. 1, 3, 6 and 11). For convenience merely hereinafter, the devices 195 and 196 are called, respectively, a roll and a drum. The roll 195 withdraws the uppermost sheet in the pile from beneath the hold-down comprising the fingers 190 and 191 to separate the sheet from the other sheets in the pile and is therefore called a separating device. The drum 196 acts upon the sheet separated by the roll 195 to deliver the separated sheet from the pile and is therefore called a delivering device. The separating and delivering devices 195 and 196 move the sheet successively in opposite directions. The separating device 195 operates upon the exposed face of the uppermost sheet in the pile adjacent its trailing edge. The delivering device 196 operates upon the exposed face of the uppermost sheet in the pile adjacent its leading edge. The separating and delivering devices are relatively movable toward and from each other to accommodate their operation to sheets of widely varying lengths.

The rotary suction roll 195 functions only when, through the bank feeding mechanism described, the trailing edge of the uppermost sheet in the pile on the table 137 is pushed within the field of operation of the roll 195. When this occurs, the separating device 195, which is a suction roll rotating about a fixed axis in a clock-wise direction viewing Fig. 1, engages the uppermost sheet and draws it from beneath the hold-down fingers 190 and 191 thus to separate the uppermost sheet from the other sheets in the pile. As soon as the leading edge of the uppermost sheet passes from beneath the hold-down fingers it snaps upwardly into the zone of operation of the delivering device 196. This device, which is a suction drum rotating about a fixed axis in a contra-clock-wise direction viewing Fig. 1, draws the separated sheet away from the separating roll 195, picks up the separated sheet bodily and delivers it from the pile. The hold-down fingers 190 and 191 prevent the leading edge of the uppermost sheet from snapping prematurely into the field of operation of the drum 196 and insure that the sheet will not be operated upon by the drum 196 until the separating roll 195 has completed its separating stroke.

Referring to Fig. 12 the bank 21 is being fed to bring the trailing edge of the uppermost sheet into the field of operation of the separating roll 195. As shown, the leading edge of the uppermost sheet is about to be engaged by the staking finger 179. Fig. 13 shows that the bank feeding mechanism has fed the leading edge of the top sheet from beneath the staking finger but not from beneath the hold-down fingers. As soon as the leading edge of the uppermost sheet in the pile is fed out of engagement with the 78

staking finger the latter drops into place upon the leading edge of the next to the uppermost sheet to maintain the pile staked. As soon as the separating device 195 withdraws the leading edge of the uppermost sheet from beneath the hold-down fingers the leading edge of the separated sheet snaps upwardly into the field of operation of the delivering drum 196 as shown in Fig. 14. The ability of the leading edge of the uppermost sheet to snap upwardly into the field of operation of the delivering drum 196 is due to the bend imparted in the pile adjacent the leading edges of the sheets. During the effective stroke of the separating roll 195 to withdraw the leading edge of the uppermost sheet from beneath the hold-down fingers, the bank is being fed in the manner heretofore described. As soon as the leading edge of the uppermost sheet is withdrawn from beneath the hold-down fingers the feed of the bank is stopped momentarily until the delivering drum 196 snatches the separated sheet from the separating roll 195. When the separated sheet is withdrawn from the roll 195 the feed of the bank is resumed to bring the trailing edge of the succeeding uppermost sheet in the pile within the field of operation of the separating roll 195.

Referring to Figs. 1 and 3 the separating device 195 comprises a cylindrical roll which is keyed to a horizontal shaft 198 journaled in the opposed arms of a yoke 199. The yoke 199 is pivoted upon a support 200 so that the position of the roll may be adjusted vertically, the extent of adjustment being controlled and maintained by an adjusting screw 201. The support 200, as shown in Fig. 2, is mounted to slide between the rails 132 in order to accommodate the operation of the roll 195 and drum 196 to sheets widely varying in length. The desired position of the support 200 longitudinally of the rails is maintained by a clamping screw.

The shaft 198 for the roll 195 is driven by a bevel gear 2010 (Fig. 1) which meshes with a similar gear 202 on one end of a flexible shaft 203. One end of the flexible shaft 203 is journaled in a bracket 204 (Fig. 3) extending from the yoke 199. The other end of the flexible shaft 203 is journaled in a bracket 205 (Figs. 3, 5 and 6) extending laterally from an arm 206 projecting rearwardly from a hub 207 secured to a horizontal rod 208. The front end of the arm 206 is forked and embraces the shaft 170. The opposite ends of the rod 208 are supported from the brackets 171 and 172 (Fig. 3). As shown in Figs. 5 and 6 the hub 206 may be adjusted laterally on the rod 208, a screw 209 being provided to hold the hub 207 in any position of lateral adjustment.

The flexible shaft 203 is driven by a bevel gear 210 which meshes with a similar gear 211 mounted on a sleeve 212 splined to the shaft 170. The face on the sleeve 212 opposite the gear 211 engages the forked end of the arm 206. Outside the bracket 172 (Fig. 3) the shaft 170 is provided with a sprocket 213 which is driven by a chain (not shown) from the machine or mechanism to which the sheets are fed so that the shaft 170 may be driven in a contra-clockwise direction, viewing Fig. 1, in timed relation with said machine or mechanism. The roll 195 and drum 196 rotate in opposite directions.

Referring to Fig. 3 the cylindrical separating roll 195 is provided with a cylindrical series of aligned rows of openings 214 and is otherwise constructed similar to the rotary cylindrical suc-

tion roll disclosed in my co-pending application hereinbefore referred to.

In order to draw atmospheric air through the roll 195 to cause the uppermost sheet in the pile to adhere to the lowermost suction cups 214 of the roll 195 it is connected by a conduit 215 to some suitable air exhauster (not shown). Intermediate its ends, the conduit 215 is connected to a valve casing 216 (Fig. 2), carried by a bracket 217 on the support 200. The conduit 215 is maintained normally closed to the atmosphere by a valve comprising a leather disk 218 (Figs. 2 and 3) carried by a cap 219 pinned to a guide stem 220 mounted to slide in a fibre bushing 221 which lines a small opening 222 (Fig. 1) in the valve 18 casing.

In order to operate the valve 218 to open the conduit 215 to the atmosphere, the cap 219 is connected by a link 223 to an armature 224 forming part of a magnet and resistance coil unit 225. The magnet part of the unit comprises a coil 226 inserted through an opening formed centrally in a series of flat plates 227 (Fig. 3) the construction being such that a portion of each of the plates passes through the central opening in the coil 226. The plates 227 are bound together by two flat metallic plates 228 (Fig. 3) each having a pair of outstanding ears 229 through which screws pass to secure the unit 225 to the vertical face of a plate 230 secured to the support 200. Interposed between the ears 229 and the vertical face of the plate 230 is an insulating plate 231. The rear side of the vertical face of the plate 230 carries clips 232 similar to fuse clips, which support a resistance coil cartridge 233. By means of the leather valve 218, the fibre bushing 221, and the insulating plate 231 the magnet unit is insulated electrically and magnetically from the machine.

Beneath the table 137 the support 200 carries a pin 234 upon which an arm 235 is mounted for pivotal adjustment. The arm 235 carries a pair of adjustable electric terminals 236 and 237 which are insulated, respectively, from the arm 235 by the insulating plates 238 and 239. The arm 235 carries a bell-crank lever 240, constructed of insulating material, the horizontal arm of which supports a switch 241 to which an electric terminal 242 is connected. The switch 241 is insulated from the machine by the insulating material of which the lever 240 is constructed. The vertical arm on the bell-crank lever 240 carries a plate 243 which is formed at its front end into three fingers 244 (Fig. 3) which extend forwardly into grooves 245 in the separating roll 195. The forward ends of the fingers 244 extend into the path of movement of the trailing edge of the uppermost sheet in the pile during its movement from beneath the hold-down under the action of the roll 195.

Normally the armature 224, which is pivoted to the unit 225, is held in the position of Fig. 2 by a spring 246 one end of which is connected to the armature 224 and the other end of which is connected to the valve body 216. Normally the fingers 244 are held in the position of Fig. 1, with the switch 241 engaged with the terminal 236, by a spring 247 which presses against the front face of the plate 243. The movement of the plate 243 under the influence of the spring 247 is limited by an adjustable screw 248. The tension of the spring 247 may be adjusted by an adjusting screw 249 which passes loosely through the plate 243. The spring 247 is coiled

about the shank of the screw 249 and interposed between the plate and a head on the screw.

As shown by the diagram in Fig. 20 the resistance coil 233 and the magnet 226 are connected in series to the electrical transmission lines independent of the switch 241. When the switch 241 contacts with the terminal 236 the magnet 226 is short-circuited and practically de-energized to release the armature 224 to the influence of the spring 246. When the switch 241 contacts with the terminal 237 the resistance coil is short-circuited and practically de-energized. This increases the energization of the magnet which retracts its armature 224 against the tension of the spring 246. With this construction the magnet 226 is energized normally, sub-normally and abnormally. When energized normally the magnet keeps its armature home. This normal energy is not sufficient, however, to operate the magnet to retract its armature when the valve 218 is closed by the spring 246. The provision of a metallic circuit which is energized independently of the switch 241 eliminates arcing between the switch 25 and the terminals 236 and 237 when switch contact is broken. The inductive discharge goes through the closed metallic circuit instead of jumping across the gap which has just been opened between the switch and one of the terminals.

In the position illustrated in Fig. 1 the magnet 226 is short-circuited or de-energized and the armature 224 is free to move under the influence of the spring 246 to close the valve 218. Thus, the conduit 215 is maintained closed to the atmosphere normally. When the roll 195 engages the uppermost sheet in the pile and withdraws it from beneath the hold-down fingers 190 and 191 to separate the sheet from the other sheets in the pile, the trailing edge of the separated sheet engages the fingers 244 thereby swinging the bell-crank lever 240 to withdraw the switch 241 from the terminal 236 and transfer the switch 241 to the terminal 237. As shown in Fig. 1 the construction is such that the switch 241 is operated by an extremely slight movement of the fingers 244 under the influence of the trailing edge of the separated sheet.

When the switch 241 contacts with the terminal 237 the resistance coil 233 is short-circuited thus increasing the normal energization of the magnet 226 sufficient to retract the armature 224 against the tension of the spring 246 to operate the valve 218 and open the conduit 215 to the atmosphere. Opening the conduit to the atmosphere does not break entirely the suctional engagement of the roll 195 with the separated sheet as the movement of the valve 218 and the size of the opening closed thereby are correlated to the aggregate sizes of the openings 214 in the roll 195 in communication at the time with the conduit 215 so that the amount of suctional engagement of the roll 195 with the separated sheet is reduced rather than destroyed. With this construction after the conduit 215 is open to the atmosphere the suction roll 195 continues to engage the separated sheet during the continued rotation of the roll with a force tending to hold the trailing edge of the separated sheet firmly against the fingers 244 thus to maintain the magnet 226 fully energized. Vibration of the fingers 244 under the influence of uneven pressure exerted by the trailing edge of the separated sheet against them results neither in a

fluttering of the valve 218 nor in arcing between the terminals and the switch 241 to which the vibrations of the fingers are transmitted. The normal flow of current through the circuit keeps the armature home after it has been retracted and provides an energized metallic circuit through which inductive discharges flow instead of jumping across the gaps formed between the vibrating switch 241 and the terminal 237. It will, however, be understood by those skilled in the art that the period in which the separated sheet is held stationary against the fingers 244 before the separated sheet is snatched away from the roll 195 by the drum 196 is very small.

In order to stop the feed of the bank when the trailing edge of the separated sheet engages the fingers 244, the bracket 53 (Figs. 1 and 4) carries a horizontal pin 250 upon which a bell-crank lever 251 is pivoted. One arm of the bell-crank lever 251 is provided with a roll 252 which engages a peripheral groove 253 formed on the sleeve 58. The other arm of the bell-crank lever 251 is connected by a link 254 to an armature 255 pivoted on a magnet unit 256. The magnet part of the unit comprises a coil 257 inserted through an opening formed centrally through a series of flat plates 258 (Fig. 4), the construction being such that a portion of each of the plates 258 passes through the central opening in the coil 257. The flat plates are bound together by two flat metallic plates 259 secured to a bracket 260 on the side-frame 29. Interposed between the plates 258 and the bracket 260 is an insulating plate 261 (Fig. 1).

As shown in Fig. 20 the magnet 257 is connected in parallel with the magnet 224. Normally the spring 247 (Fig. 1) maintains the magnets 226 and 257 short-circuited so that their armatures 224 and 255 are free to move, under the influence of the springs 246 and 60, away from the magnets 226 and 257 thus to maintain the conduit 215 closed to the atmosphere and the clutch members 56 and 57 engaged to drive the bank along the two supply tables 22 and 24. When the trailing edge of the uppermost sheet actuates the fingers 244 to transfer the switch from the terminal 236 to the terminal 237 both magnets 226 and 257 are energized simultaneously to open the conduit 215 to the atmosphere and to separate the clutch members 56 and 57 to stop the feed of the bank. With this construction the bank formed on the upper supply table 22 is fed continuously until the trailing edge of the uppermost sheet in the front end of the bank is drawn by the roll 195 into engagement with the fingers 244 when the feed of the bank, both the portion on the table 22 and the portion on the table 24, is suspended for the extremely brief period necessary for the drum 196 to snatch the separated sheet away from the roll 195 at which time the spring 247 returns the fingers 244 and the switch 241 to their normal positions (Fig. 1). The return of the switch 241 to its normal position operates the electrical connections described to close the valve 218 and the clutch members 56 and 57.

As shown in Fig. 11 the delivering drum 195 which snatches the separated sheet from the roll 195 and delivers it from the pile comprises two sections 262 and 263 dovetailed together. Each section comprises a hub 264, splined to the shaft 170, a web 265 and a peripheral surface 266. Each section is provided with a series of peripheral openings 267 each one communicating with a

blind passage 268. Each one of the blind passages has an opening 269 on the side of the peripheral surface 266 opposite the web 265.

In order to draw atmospheric air through the drum 196, its faces, provided with the openings 269, are engaged respectively by valve disks 270 and 271. The disk 270 has a hub 272 which fits loosely over the hub 264 of the drum section 263. The disk 270 is held from rotation on the hub 264 by a pair of screws 273 (Fig. 6) which are carried by the outside face of the disk 270 and embrace a lug 274 projecting upwardly from the forked end of the arm 206. The inside face of the disk 270 is provided with a groove 275 which communicates with the openings 269 during the rotation of the drum 196. The inside face of the disk 270 is provided with another groove 276, but this groove has no operative communication with the openings 269 during the rotation of the drum 196. The groove 276 is merely provided as a constructional expedient to balance the groove 275 and to form a uniform seat for the end face of the drum during its rotation against the inside face of the disk 270. The disk 270 is pressed against the face of the drum 196 containing the openings 269 by a spring 277 which is coiled about the hub of the disk 270 and located between the body portion of the disk and a plate 278 interposed between the drum 196 and the forked end of the arm 206. The inside face of the disk 271 is also provided with a groove 279 which communicates with the openings 269 during the rotation of the drum 196. The inside face of the disk 271 is also provided with a groove 280 having the same function as the groove 276. The disk 271 is also held from rotation on the hub 264 by a pair of screws 281 (Fig. 5) which are carried by the outside face of the disk 271 and which embrace a lug 282 carried by the free end of an arm 283 projecting rearwardly from the hub 207. The free end of the arm 283 is forked to embrace the shaft 170. The disk 271 is pressed against the face of the drum 196 containing the openings 269 by a spring 284 which is coiled about the hub of the disk 271 and interposed between the body portion of the disk 271 and a plate 285 interposed between the drum 196 and the forked end of the arm 283.

With this construction, by loosening the set screws 209 the hub 207 may be adjusted laterally on the rod 208. As the forked ends of the arms 206 and 283 embrace the shaft 170 on opposite sides of the delivering drum 196 it is moved laterally on the shaft 170 when the hub 207 is moved laterally on the rod 208. During this lateral movement of the delivering drum 196 and the hub 207 the gears 210 and 211 move laterally with the arm 206, the gear 210 because it is supported from the arm 206 and the gear 211 because its sleeve 212 rotates in contact with the forked end of the arm 206.

In order to draw atmospheric air through both sections of the drum 196 the outside faces of the disks 270 and 271 carry conduits 286 and 287 (Figs. 5 and 11). Each conduit communicates with a circular opening formed through its adjacent disk in position to communicate with the groove 275, in the case of the disk 270, and the groove 279, in the case of the disk 271, during the rotation of the drum. The conduits 286 and 287 are connected to the air-exhausting system (not shown) to which the conduit 215 is connected.

As shown in Fig. 6 the conduit 286 is positioned 76 to draw air through all the openings 267 in the

drum section 263 in communication with the groove 275 in the valve disk 270. In the position shown in Fig. 6 the conduit 287 draws air through all the openings 267 in the drum section 262 in communication with the groove 279 in the valve disk 271.

In order to close all the openings 267 in communication with the grooves 275 and 279, respectively, except two of them, one in each drum section, so that the conduits 286 and 287 may exhaust air from the drum and thus produce a suctional effect with these two openings to cause the exposed face of the separated sheet adjacent its leading edge to adhere to the periphery of the drum 196 as shown in Fig. 14, the periphery of the drum 196 is partially covered by a band 288 (Figs. 5, 6, 12, 13 and 14). The band 288, which is driven by friction from the drum 196, or the paper sheet, during the rotating of the drum 196, is supported by a frame comprising two spaced plates 289 and 290 which are pivoted on a horizontal pin 291 carried by the front ends of brackets 292 and 293 (Fig. 1) projecting forwardly from the cap 159. The plates 289 and 290 are connected together by the tie-rods 294 and 295.

The pin 291, between the brackets 292 and 293, supports a roll 297 under and over which the band 288 passes. The upper run of the band 288 passes over a roll 297 rotatably mounted on a bolt 299 having a cylindrical head 299 on one end which fits into a countersunk portion on one end face of the roll. The other end of the bolt 299 is threaded and extends through a slot 300 formed in the plate 289. Outside the plate 289 the bolt 299 is provided with a washer 301 and is threaded to receive a nut 302 by means of which the roll 297 may be clamped to the plate 289 in a manner permitting the free rotation of the roll. The slot 300 is provided so that the position of the roll 297 may be changed to maintain the band 288 taut. From the roll 297 the band 288 passes around a roll 303 journaled on a pin 304 carried by the rear ends of the plates 289 and 290. From the roll 303 the band 288 passes in contact with the periphery of the drum 196 to the roll 297.

The portion of the band 288 in contact with the periphery of the drum 196 is held against the drum under pressure so that the band may be wrapped partially around its periphery. To this end the brackets 292 and 293 carry a horizontal rod 305 upon which a rod 306 is pivoted. The free end of the rod 306 passes loosely through an opening formed in a block 307 and a rock-shaft 308 to which the block is secured. The opposite ends of the rock-shaft 308 are journaled on the plates 289 and 290. Coiled around the rod 306 and interposed between a shoulder on the rod and the block 307 is a spring 309. With this construction the band 288 is held against the periphery of the drum 196 by the pressure of the spring 309. Moreover, the band frame, comprising the connected plates 289 and 290, may be thrown upwardly into the construction line position of Fig. 6 to permit access to that portion of the periphery of the drum 196 normally covered by the band 288.

Referring to Fig. 14 continued rotation of the drum 196 causes the pair of openings 267, forming suction cups in the periphery of the drum 196 to which the exposed face of the separated sheet adjacent its leading edge adheres, to pull the sheet in between the periphery of the drum and the band 288. That is, the suction cups indicated at A, Fig. 14, pull the sheet in between the drum and 75

the band 288. By manipulation of the screws 273 and 281 the rotative positions of the valve disks 270 and 271 may be varied in order to change the time in the rotation of the drum 196 at which the suction cups A come within the suctional influence of the conduits 286 and 287. The next succeeding pair of suction cups, indicated at B, Fig. 14, then register with the grooves 275 and 279 in the valve disks 270 and 271 and air is exhausted from the cups B to cause the exposed face of the separated sheet to adhere thereto. This action continues as the succeeding suction cups register successively with the grooves 275 and 279 until a sheet is wrapped around the periphery of the drum throughout an arc concentric with the grooves 275 and 279.

When the suction cup indicated at A passes beyond the upper ends of the grooves 275 and 279, said point being indicated at C (Fig. 6), the suction cups A are open to atmospheric air and the leading edge of the separated sheet is free to leave the periphery of the drum. During the continued rotation of the drum the leading edge of the separated sheet is pushed into engagement with three tapes 310, which feed the separated sheet to the usual registry board (not shown). While the separated sheet is being transferred from the drum 196 to the feeding tapes 310 the suction cups which cause the sheet to adhere to the periphery of the drum are opened to the atmosphere successively as they pass the point C (Fig. 6).

In the meantime, and while the operative openings 267 in the periphery of the drum are covered by the first separated sheet, except two, a second separated sheet is engaged by the suction cups A (Fig. 14) to repeat the cycle described. The suction cups A may be the same pair referred to or a different pair, depending upon the length of the sheets being delivered from the pile by the drum 196. From this it will be apparent that the only function of the band 288 is to prepare the drum 196 for the reception of the first sheet. After the first sheet is on the drum the successive sheets are drawn thereon without assistance from the band 288. Of course, the band 288 would function, if a break came in the continuity of the separation of the sheets from the pile, after the break, exactly as in the case of the first sheet hereinbefore referred to.

The central feeding tape 310 passes about a roll 311 (Figs. 3 and 15) on a horizontal shaft 312 (Fig. 16) the opposite ends of which are journaled in a frame 313, one end of which is supported from the machine or mechanism to which the sheets are fed and the other end of which rests on the rod 208. The right hand feeding tape 310 passes about a roll 314 (Figs. 3 and 15) on the shaft 312. The left hand feeding tape 310 passes about a roll 314 (Figs. 3 and 15) which is supported by the shaft 312. The rolls 314 flank the roll 311.

The sheet is pressed into engagement with the central feeding tape 310 by a rubber roll 315 mounted to rotate loosely between collars 316 and 317 fixed to a rod 318 the opposite ends of which are removably mounted on the frame 313.

In order to bridge the gap between the drum 195 and the portions of the feeding tapes 310 passing over the tape-feeding rolls, the frame 313 carries a horizontal rod 319 upon which is mounted for lateral adjustment two fingers 320 (Figs. 3, 15, 16 and 18) projecting rearwardly into positions on opposite sides of the drum 196. These fingers 320 have a flat upper surface 321 which

guide the sheet into the bight of the rolls 311 and 315. The fingers 320 also aid in stripping the sheet from the drum 196.

Cooperating with each of the fingers 320 is a finger 322 which projects rearwardly from a hub 323 secured to the rod 318 by a set screw 324. The hub 323 has a tail 325 to facilitate the adjustment of the hub laterally of the rod 318 when the screw 324 is loosened and also to aid in guiding the sheets ejected by the ejecting mechanism to be described. The finger 322 is provided with a lower flat surface 326 which cooperates with the surface 321 to form a guide slot for the passage of the sheet to the feeding tapes.

The feeding tapes feed the sheet over the usual registry board (not shown) beneath a pair of fingers 327 (Figs. 3, 15 and 16). The fingers 327 project rearwardly from a hub 328 mounted for lateral adjustment on a rod 329 removably supported by the frame 313. Guarding the entrance to the space beneath each finger 327 is a sheet switch 330 (Figs. 3, 15, 16 and 19). Each switch 330 projects rearwardly from a hub 331 secured to a horizontal shaft 332 the opposite ends of which are balanced upon the pointed ends of screws 333 and 334 adjustably secured to the opposite sides of the frame 313. With this construction the shaft 332 may rock readily. The rock-shaft 332 is provided with a tail 3330 the free end of which is connected to the frame 313 through a coiled spring 3340. To this end the opposite ends of the spring 334 are connected to pins 335 and 336 carried respectively by the tail 3330 and the frame 313. The tail 3330 is also connected to the lower end of a vertical link 337 the upper end of which is pivoted to one end of a link 338 the other end of which is pivoted at 339 to a magnet unit 340. The upper surface of the link 338 carries the armature 341 of a magnet coil 3400. This magnet is inserted through an opening formed centrally in a series of flat plates 342 (Fig. 19), the construction being such that a portion of each of the plates passes through the central opening in the coil. The plates 342 are bound together by two flat metallic plates 343 each having a pair of outstanding ears 344 through which screws pass to secure the unit 340 to the horizontal face of a bent plate 345 the vertical face of which is secured to the frame 313. Interposed between the ears 344 and the plate 345 is an insulating plate 346. Normally the spring 334 holds the switch 330 in the position of Fig. 16. In this position the magnet 340 is de-energized to permit the armature 341 to drop or be moved by the spring 3340 into the position of Fig. 16.

By the use of suction devices, specifically a roll and a drum, operating successively to separate and deliver the same sheet, an important advance in sheet feeding has been made. If through static electricity, unfavorable atmospheric conditions or badly severed sheets, a plurality of sheets are separated from the pile by the suction separating device when the suction delivering device operates to drag them away from the suction separating device to deliver them from the pile the two sheets will fan enough to allow the separating device to exert suction on the narrow lap of the underlying second sheet and thus prevent the delivering device from delivering more than one sheet at a time from the pile. It sometimes happens, however, that the sheets are stuck together mechanically, as by ink. In that case the sheets stuck together will be separated

and delivered from the pile as a unit. To prevent such a plural sheet unit from being fed to the machine or mechanism to which the single sheets are fed the illustrated embodiment of the 5 invention is provided with an ejecting mechanism for ejecting from the machine a plurality of stuck-together sheets. This ejecting mechanism is controlled by a caliper mechanism for detecting the presence of the said plurality of 10 sheets being delivered from the pile by the delivery mechanism.

In order to caliper the sheet being fed from the delivering drum 196 to the feeding tapes 310 for the purpose of detecting that a plurality of 15 stuck together sheets has been separated and delivered as a unit from the table 137, the machine is provided with a caliper roll 347 (Figs. 15, 16, 17 and 19) mounted to rotate in contact with the periphery of the drum 196. The roll 20 347 is secured to one end of a stub shaft 348 which is journaled in the hub of a bell-crank lever 349. The shaft 348 is held from longitudinal movement in the hub of the lever 349 by the hub of the roll 347 on one end of the shaft and by a 25 collar 350 on the other end of the shaft 348. The horizontal arm of the bell-crank lever 349 is pivoted on the lower arm of a second bell-crank lever 351, pivoted centrally on a horizontal pin 352 one end of which is carried by the arm 30 292 and the other end of which is carried by a bracket 353. The bracket 353 is secured to a plate 354 (Fig. 18) carried by the arm 292. The upper end of the bell-crank lever 351 is provided with an insulating plate 355 which carries a 35 switch 356 having an electrical contact 357 on its free end. This terminal 357 is adapted, on occasion, to contact with an electrical terminal 358 carried by one end of a plate 359 secured through an insulating plate 3590, to the supporting plate 40 354.

As shown in Fig. 18 the terminals 357 and 358 are connected through the switch 356 in series with the magnet 340. Normally the switch terminal 357 is maintained out of contact with the 45 terminal 358 by a coiled spring 360 one end of which is connected to a pin 361 on the plate 354 and the other end of which is connected to a pin 362 on the upper end of the bell-crank lever 351.

Normally the caliper roll 347 is free to rise 50 upwardly under the influence of a single sheet passing between the caliper roll and the drum 196. To this end the vertical arm of the bell-crank lever 349 is provided with a block 363 which is spaced from an adjusting screw 364, carried by 55 the lower end of the bell-crank lever 351, a distance slightly greater than the thickness of the paper in the sheets being fed. The screw 364 is provided with an adjusting nut 365 so that the 60 normal space between the block 363 and the end of the screw 364 may be varied. The desired adjustment may be maintained by a butterfly nut 366 on the screw 364.

When more than one sheet at a time passes 65 between the caliper roll 347 and the periphery of the drum 196 the bell-crank lever 349 swings on its pivot, the block 363 on the upper end of the bell-crank lever 349 contacts with the end of the screw 364, and the bell-crank lever 351 swings on the pin 352 against the tension of the spring 360 70 to engage the switch terminal 357 with the terminal 358. Referring to Fig. 16 it will be apparent that the axes of the shafts 170 and 348 and the axis of the pivot pin 352 are not in line. 75 In effect the axis of the shaft 348 forms the float-

ing pivot of a toggle the links of which may be considered as being pivoted on the shaft 170 and pivot pin 352. Thus the toggle is maintained in a slightly broken condition normally. With this construction the broken condition of the toggle is increased when two or more sheets pass between the surfaces of the drum 196 and the caliper roll 347. This plurality of stuck-together sheets first causes the upper end of the bell-crank lever 349 to contact with the end of the screw 364 and then causes the bell-crank lever 351 to swing on the pin 352 in a contra-clockwise direction viewing Fig. 18 to close the circuit through the engagement of the terminals 357 and 358. When this occurs the magnet 340 is energized. The energized magnet retracts its armature 341 thus rocking the shaft 332 in a clockwise direction (Fig. 18) against the tension of the spring 334 to depress the sheet switches 330 into engagement with the outside tapes 310, respectively. When this occurs the leading edges of the plurality of sheets engage the upper surfaces of the depressed sheet switches 330 which direct the plurality of sheets through the space between the sheet switches 330 and the tails 325 to a pair of slats 367, (Fig. 1) one end of each of which is supported from the machine or mechanism to which the sheets are fed and the other end of each of which is suitably supported from the frame 313.

It will be apparent to those skilled in the art, taking into consideration the different sizes, thicknesses and materials that a commercial sheet feeding machine is called upon to deliver and the various effects different atmospheric conditions have upon the sheets handled, that on some jobs it may not be necessary to employ in one machine all the described features of the illustrated embodiment of the invention which is designed particularly for universal use. When feeding sheets 40 of extremely thin paper or sheets having their leading edges curved downwardly, the leading edge thereon may not be able to snap from beneath the hold-down fingers 190 and 191 into the field of operation of the delivery drum 196 notwithstanding the bend in the pile produced by the abutment rolls 109 and the band feeding roll 110. In such cases the leading edge of the thin sheet is thrown upwardly by a winding device 368 (Figs. 1, 3, 5 and 6) which may be employed to supplement the bending action of the rolls 109 and 110, or which may be employed independent of any bend in the bank, to bring the leading edge of the thin sheet into the field of operation of the delivering drum. 50

The winding device 368 comprises a cylindrical blowing tube 369 which is mounted for vertical and rotative adjustment on the hub 207 the desired adjustment being maintained by a set screw 370. One end of the tube 369 communicates with a flexible conduit 371 which is suitably connected to an air blowing system (not shown). The other end of the tube 369 is blind. Adjacent its blind end the tube 369 is provided with an orifice 372 which may be circular or elongated, comprising 65 a nozzle through which the air is blown over the exposed face of the top sheet in the pile. In order to induce the current of air blown out of the orifice 372 to flow upwardly away from the exposed face of the top sheet in the pile the jet 70 issuing from the orifice 372 impinges against a surface 373, spaced therefrom. In the illustrated embodiment of the invention the surface 373 is curved and is formed on the bottom of a plate 374 substantially rectangular in plan (Fig. 5). 75

The plate 374 is formed integral with the arms of a yoke 375 projecting rearwardly and downwardly from a collar 376 adjustably mounted vertically on the tube 369 to permit the jet issuing from 5 the orifice 372 to strike the curved surface 373 different distances along its periphery.

As shown in Fig. 6 the convex-surface 373 from the point 377 to the point 378 has the curvature of a cylinder which merges into a curvature 379 10 directed rearwardly and upwardly. When the air from the orifice 372 strikes the curved surface 373, the air, instead of passing said surface tangentially or being deflected downwardly thereby, hugs the curved surface 373 and then flows 15 in close engagement with the bottom of the plate throughout its length. The air is thus induced to flow upwardly away from the exposed face of the uppermost sheet. This upward movement of the air produces a condition of unbalanced 20 pressure between the upper and lower surfaces of the uppermost sheet in the pile and thus permits atmospheric air to elevate the leading edge of the uppermost sheet in the pile into the field of operation of the delivering drum. The only purpose 25 of the foot 374 from the point 378 to the rear end of the plate is to prolong the condition of unbalanced pressure and transmit it as close to the leading edge of the separated sheet as possible considering the difficulty of locating the 30 wincing device underneath the drum 196.

The important features of the winding device 368 are the orifice 372 and the convex-surface 373 against which the jet from the orifice impinges. The surface 373 may be a plane as the 35 best results are not obtained necessarily when the jet is caused to impinge against a curved surface. The jet of air hugs the curved surface against which it strikes instead of passing by the curved surface tangentially, or being deflected 40 thereby downwardly, and is thus induced to flow upwardly away from the top sheet. With this method of blowing air over the exposed face of the uppermost sheet in a pile and inducing the air to flow away from said face, a condition of 45 unbalanced pressure is produced on opposite sides of said sheet so that the leading edge of the uppermost sheet is elevated by atmospheric air, acting upon the under side of the sheet, into the field of operation of the delivering drum. Experience 50 has demonstrated that the winding device 368 operates to elevate the leading edge of the uppermost sheet in the pile independently of the bend shown in Fig. 6. Experience has also demonstrated that the closer the curved surface 373 is 55 to the orifice 372 and the further the path of the jet strikes the curved surface away from a tangent of the curved surface 373 parallel to the path of the jet, the greater is the efficiency.

In considering the winding device 368, therefore, it must be understood that the particular kind and shape of surface against which the jet impinges, the particular space between the orifice 372 and the curved surface 373, the particular part of the curved surface against which the 60 jet impinges, and the particular extension on the plate beyond the curved surface 373 herein disclosed are provided merely because they are well suited to the conjoint features of the illustrated embodiment of the present invention. In fact, 65 when the winding device 368 is applied to the machine disclosed in my application hereinbefore referred to, to elevate the uppermost sheet in the pile into the field of operation of the delivering drum, the orifice 372 may discharge its

jet against a surface 373 of a cylinder or it may be a ball 374 on a line closely approaching a horizontal diameter thereof and in a plane substantially parallel to and spaced from the exposed face of the top sheet in the pile. The cylinder or ball 374 is soldered in close proximity to the blowing tube 369 so that the space between the orifice 372 and the surface 373 against which the jet impinges is small. With this construction, which is disclosed in Fig. 21, the jet of air 10 hugs the surface of the cylinder or ball through an arc exceeding 90 degrees.

The jet of air may be discharged from the orifice 372, with excellent results, on a line substantially normal to the exposed face of the top sheet 15 in the pile, and the exposed face of the sheet itself may be used to induce the jet of air to bend out of its normal path thus to produce a condition of unbalanced pressure on the opposite faces of the top sheet. When discharging the air in 20 a direction substantially normal to the exposed face of the top sheet in the pile it is preferred to provide the tube 368 with an orifice 375 (Figs. 22 and 23) through which the air is discharged vertically downward. Interposed between the 25 exposed face of the top sheet in the pile and the orifice 375 is a plane surface 376 arranged substantially parallel to the exposed face of said top sheet. As shown, the plane surface 376 is formed by one face of a disc 377 supported from 30 a collar 378 on the tube 368 by wires 379 soldered to the collar 378 and to the periphery of the disc 377.

When the jet from the orifice 375 strikes the plane surface 376, or it may be the exposed face 35 of the top sheet, the air spreads laterally and produces a condition of unbalanced pressure on the opposite faces of said top sheet thus inducing the elevation of at least a portion of the top sheet from the pile.

Referring again to Fig. 1 the bank feeding bands 32 and 62 may be driven at the same rate of speed. This speed may be varied by means of the transmission mechanism (not shown) 45 through which the pulley 59 is driven. By removing the gears 37 and 39 from the ends of the shaft 34 and the stud 39, respectively, and replacing said gears with similar gears having different ratios, the band 32 may be driven at a different speed than the band 62. This differential drive 50 of the bands 32 and 62 fans out the sheets in the bank as it passes through the throat 23.

As described hereinbefore, the delivering drum 196 operates to pick up the separated sheets one 55 at a time from the pile in rapid succession and thus deliver to the registry board mechanism a continuous stream of individual sheets. In order to correlate the timing between the operation of the delivering drum 196 and the operation of the mechanism to which the sheets are delivered 60 for a subsequent operation the conduits 286 and 287 are connected to a branch conduit 380 (Figs. 2, 5, 24 and 25) which communicates through a nipple 381 (Figs. 24 and 25) with the interior of a valve casing 382 secured to the arm 191. As 65 shown in Fig. 3 the separating roll conduit 285 also communicates with the interior of the valve casing 382 which is connected to a suitable air exhauster (not shown) through a conduit 383.

Mounted within the valve casing 382 is a piston valve 384 provided with cylindrical heads 385 and 386 connected together by a cylindrical shank 387 of reduced diameter. The head 385 carries a weight 388 which maintains a curved surface 389 on the head 386 engaged with the 70

peripheral edge of a cam 390 mounted on the shaft 170. With this construction the valve 384 is reciprocated in the valve casing 382 during the rotation of the shaft 170 which is driven, from the mechanism to which the sheets are delivered, and which in turn drives the delivering drum 196.

When the valve 384 is reciprocated by the cam 390 into its extreme upward position both of the conduits 215 and 380 communicate with the space between the valve casing 382 and the shank 387 on the piston valve. The conduits 215 and 380 are thus in communication with the air exhauster through the conduit 383. When the valve 384 follows the cam 390 into its extreme downward position the head 385 covers the port for the conduit 380 thus disconnecting the conduits 286, 287 and 380 communicating with the delivering drum 196 from the air exhausting system. With this construction the delivering drum 196 is connected to the air exhausting system during a definite period only in the cycle of operations of the mechanism to which the sheets are fed for a subsequent operation.

In order that the machine may be converted instantly from a machine of the continuous delivery type to one of the intermittent or timed feed type, the head 385 is provided with a lateral pin 391 through which the piston valve 384 may be rotated within the casing 382. When the pin 391 is positioned within a slot 392 on the valve casing 382 the piston valve is held in its extreme upward position to insure the continuous operation of the delivering drum 196.

By elevating the pin 391 and by rotating it and the valve 384 through an arc of 180 degrees, the pin 391 may be positioned in a vertical slot 393, longer than the slot 392, so that the valve 384 may be reciprocated by the cam 390 to insure the operation of the delivery drum 196 in timed relation to the mechanism for performing a subsequent operation upon the delivered sheets.

In addition to the automatic means for varying the suctional pull of the roll 195 on the sheet during its rotation the valve casing 216 is provided with a pet-cock 394 (Figs. 1 and 2) so that the operative may bleed the air exhausting system to reduce the amount of air drawn through the roll 195. The valve casing 382 is also provided with a valve 395 (Fig. 25) but this valve controls a large opening 396 in the left side face of valve casing 382 so that when it is uncovered by the valve 395 substantially all the atmospheric air drawn into the air exhausting system enters through said opening 396. The valve 395 may be used as a starting and stopping mechanism independent of the power drive as the roll 195 and the drum 196 rotate without effect upon the sheet when the valve 395 is moved to open the valve casing 382 to the atmosphere. The valve 395 is formed on one face of a lever 397 near the lower end thereof. The lever 397 is pivoted on a headed pin 398 projecting laterally from the left-side face of the casing 382. The lever 397 is provided with an operating handle 399 by means of which it may be swung from a position where it engages a stop pin 400 (Fig. 25), in which position the valve 395 covers the opening 396, to a position where the opening 396 is uncovered. The valve 395 is pressed against the left-side face of the casing 382 by a spring 401 coiled about the pin 398 and interposed between the head thereon and the lever 397.

In order to condition the sheets to facilitate their feeding and their handling in a subsequent

operation and to eliminate static electricity the conduit 371 for conducting the air to the winding device 368 is connected to one of the columns 31 (Figs. 1 and 3). This column is hollow and constitutes a reservoir for water or other liquid 402 (Fig. 1) through which air from a conduit 403 is blown. The conduit 403 is suitably connected to an air blowing system (not shown). The water in the hollow column is replenished through a plug 404. With this construction the air for the winding device is saturated. This saturated air conditions the sheets so that they may be readily fed or handled both in the feeding machine and the mechanism to which the sheets are fed. The saturated air also conditions the sheets so that the tendency of the sheets to adhere under the influence of static electricity is obviated.

Nothing herein explained is to be interpreted as limiting the various inventions in the scope of their application to use in connection with the particular apparatus or the particular mode of operation or both selected for purposes of illustration and explanation. While the particulars of construction herein set forth are well suited to one mechanical form of the invention, it is not limited to these details of construction, nor to the conjoint use of all its features, nor is it to be understood that these particulars are essential since they and the steps of the methods disclosed may be modified within the skill of the artisan without departing from the true scope of the actual inventions, characterizing features of which are set forth in the following claims by the intentional use of generic terms and expressions inclusive of various modifications.

What is claimed as new, is:

1. That improvement in the art of handling a supported sheet which consists in discharging air at a point above the exposed face of the supported sheet and deflecting the air after its discharge to produce a condition of unbalanced pressure on the opposite faces of the sheet whereby atmospheric air acting on the face of the sheet opposite its exposed face elevates at least a portion of the sheet from the support.

2. That improvement in the method of producing a condition of unbalanced pressure on the opposite faces of a supported sheet to induce the elevation of at least a portion of the sheet from its support which consists in discharging a jet of air at a point above the exposed face of the supported sheet and deflecting the jet away from the sheet after its discharge.

3. That improvement in the method of producing a condition of unbalanced pressure on the opposite faces of a supported sheet to induce the elevation of at least a portion of the sheet from its support which consists in discharging air at a point above the exposed face of the sheet in a direction substantially parallel thereto and causing the discharged air to flow away from the sheet.

4. That improvement in the method of producing a condition of unbalanced pressure on the opposite faces of a supported sheet to induce the elevation of at least a portion of the sheet from its support which consists in discharging a jet of air at a point above the exposed face of the sheet in a direction substantially parallel thereto and causing the discharged jet to impinge against a convex surface located above the exposed face of the sheet.

5. That improvement in the method of producing a condition of unbalanced pressure on the

5 opposite faces of a supported sheet to induce the elevation of at least a portion of the sheet from its support which consists in blowing air above the exposed face of the sheet and causing the air to detour away from the sheet, out of its normal path, in engagement with a surface spaced from the sheet.

6. That improvement in the method of producing a condition of unbalanced pressure on the 10 opposite faces of a supported sheet to induce the elevation of at least a portion of the sheet from its support which consists in discharging a jet of air above the exposed face of the sheet, and causing the discharged jet to detour away from the sheet, out of its normal path, in engagement with a surface spaced from the sheet.

7. That improvement in the method of producing a condition of unbalanced pressure on the 20 opposite faces of a supported sheet to induce the elevation of at least a portion of the sheet from its support which consists in discharging a jet of air above the exposed face of the sheet and deflecting the discharged jet away from the sheet out of its normal path through its impingement 25 against a surface.

8. In a device for producing a condition of unbalanced pressure on the opposite faces of a supported sheet to induce the elevation of at least a portion of the sheet from its support, the combination with means for blowing air above the exposed face of the sheet, of means interposed in the path of the air current to cause it to flow away from the sheet.

9. In a device for producing a condition of unbalanced pressure on the opposite faces of a supported sheet to induce the elevation of at least a portion of the sheet from its support, the combination with means for blowing air above the exposed face of the sheet, of a convex-surface 40 against which the air impinges.

10. In a device for producing a condition of unbalanced pressure on the opposite faces of a supported sheet to induce the elevation of at least a portion of the sheet from its support, the combination with a nozzle through which a jet of air is blown above the exposed face of the sheet, of a convex-surface against which the jet impinges.

11. In a device for producing a condition of unbalanced pressure on the opposite faces of a supported sheet to induce the elevation of at least a portion of the sheet from its support, the combination with a nozzle through which air is blown above the exposed face of the sheet, of a convex-surface, spaced from the nozzle, against 55 which the jet impinges.

12. In a device for producing a condition of unbalanced pressure on the opposite faces of a supported sheet to induce the elevation of at least a portion of the sheet from its support, the combination with a nozzle through which air is blown above the exposed face of the supported sheet, of a convex-surface, spaced both from the nozzle and the supported sheet, against which the jet impinges.

13. In a sheet feeding machine, the combination with means for supporting a pile of sheets and means for discharging a jet of air over the top sheet in the pile, of a cylindrical surface, having its center of curvature extending substantially 60 parallel to the exposed face of the sheet and located above the cylindrical surface, against which the jet impinges.

14. In a sheet feeding machine, the combination with means for supporting a pile of sheets, 75 a hold-down for staking the pile, means for with-

drawing the top sheet in the pile from beneath the hold-down, and means for withdrawing the separated sheet from the pile, of means for elevating at least a portion of the separated sheet into the field of operation of said delivering means comprising a nozzle for blowing a jet of air above the exposed face of the separated sheet and a surface against which the jet impinges to cause the air to flow away from the top sheet.

15. In a sheet feeding machine, the combination with a hold-down for staking a pile of sheets adjacent their leading edges, a suction device engaging the exposed face of the top sheet for withdrawing it from beneath the hold-down, and a suction device engaging said exposed face 15 for delivering the separated sheet from the pile, of means for elevating the leading edge of the separated sheet into the field of operation of the delivering device comprising an air nozzle and a surface spaced therefrom and against which 20 the jet of air from the nozzle impinges to cause the air to flow away from the top sheet.

16. In a sheet feeding machine, the combination with a table for supporting a pile of sheets, a device for separating the top sheet from the 25 pile, a rotary suction device for delivering the separated sheet from the pile, and means for operating said devices to move the sheet successively in opposite directions, of means for replenishing the pile on the table automatically. 30

17. In a sheet feeding machine, the combination with a table for supporting a pile of sheets, a rotary suction device for separating the top sheet from the pile, a rotary suction device for delivering the separated sheet from the pile, and means for rotating said devices in opposite directions, of means for replenishing the pile on the 35 table automatically.

18. In a sheet feeding machine, the combination with a table for supporting a pile of sheets, 40 mechanism for replenishing the pile on the table automatically, and a device for separating a sheet from the pile, of means controlled by one edge of the sheet for limiting the separating stroke of said device and stopping said mechanism. 45

19. In a sheet feeding machine, the combination with a table for supporting a pile of sheets, mechanism for replenishing the pile on the table automatically, and a suction device for separating 50 a sheet from the pile, of means controlled by the sheet for varying the suctional pull of the device on the sheet and stopping said mechanism.

20. In a sheet feeding machine, the combination with a table for supporting a pile of sheets, 55 mechanism for replenishing the pile on the table automatically, and a device for separating a sheet from the pile, of means controlled by the trailing edge of the sheet for limiting the separating movement of the sheet and stopping said mechanism. 60

21. In a sheet feeding machine, the combination with a table for supporting a pile of sheets, mechanism for replenishing the pile on the table automatically including a clutch for starting and stopping said mechanism, a suction roll for separating a sheet from the pile, a conduit connected to the roll for drawing air therefrom, and a valve in the conduit, of means controlled by the trailing edge of the sheet for operating said valve to 70 open the conduit to the atmosphere and for operating said clutch to stop said mechanism.

22. In a sheet feeding machine, the combination with a table for supporting a pile of sheets, mechanism for replenishing the pile on the table 75

- automatically including a clutch for starting and stopping said mechanism, a suction roll for separating a sheet from the pile, a conduit connected to the roll for drawing air therefrom, a valve in the conduit, and electrical means for operating the valve to open the conduit to the atmosphere and for operating said clutch to stop said mechanism, of means controlled by the trailing edge of the sheet for throwing the electrical means into operation.
23. In a sheet feeding machine, the combination with a table for supporting a pile of sheets, mechanism for replenishing the pile on the table automatically including a clutch for starting and stopping said mechanism, a suction roll for separating a sheet from the pile, a conduit connected to the roll for drawing air therefrom, a valve in the conduit and means normally maintaining the conduit closed to the atmosphere and the clutch thrown in, of means controlled by the trailing edge of the sheet for operating the valve to open the conduit to the atmosphere and for throwing out the clutch.
24. In a sheet feeding machine, the combination with a table for supporting a pile of sheets, mechanism for replenishing the pile on the table automatically including a clutch for starting and stopping said mechanism, a suction roll for separating a sheet from the pile, a conduit connected to the roll for drawing air therefrom, a valve in the conduit, a magnet circuit including an armature operatively connected to the valve, a magnet circuit including an armature operatively connected to the clutch, said magnet circuits being connected in parallel, and means for maintaining normally the magnets de-energized with the conduit closed to the atmosphere and the clutch thrown in, of means controlled by the trailing edge of the sheet for energizing the magnets and operating the valve to open the conduit to the atmosphere and the clutch to throw it out.
25. In a sheet feeding machine, the combination with a table for supporting a pile of sheets, mechanism for replenishing the pile on the table automatically including a clutch for starting and stopping said mechanism, a suction roll for separating a sheet from the pile, a conduit connected to the roll for drawing air therefrom, a valve in the conduit, a magnet circuit including an armature operatively connected to the valve, a resistance coil, said resistance coil and magnet being connected in series, a magnet circuit including an armature operatively connected to the clutch, said magnet circuits being connected in parallel, and means for maintaining normally the resistance coil energized, the magnets de-energized, the conduit closed to the atmosphere, and the clutch thrown in, of means controlled by the trailing edge of the sheet for short-circuiting the resistance coil, energizing the magnets and operating the valve to open the conduit to the atmosphere and the clutch to throw it out.
26. In a sheet feeding machine, the combination with an upper supply table and a yielding lower supply table, of an automatically expanding and contracting bank reversing throat therebetween partially supported by the lower supply table.
27. In a sheet feeding machine, the combination with an upper supply table, a yielding lower supply table and a normally closed reversing throat therebetween partially supported by the lower supply table, of means controlled by the bank for expanding and contracting the throat.
28. In a sheet feeding machine, the combina-

tion with an upper supply table, a yielding lower supply table and a reversing throat therebetween partially supported by the lower supply table, of means for permitting the bank to open the throat for the passage of the bank therethrough.

29. In a sheet feeding machine, the combination with an upper supply table, a lower supply table, and bands for feeding a bank over the tables, respectively, of means for permitting the lower supply table to yield and for maintaining the bands engaged with each other normally, said means permitting the bands to separate to allow the passage of the bank therebetween.

30. In a sheet feeding machine, a supply table, means for feeding a bank thereover, and a fixed abutment between which and the table the bank is fed, of means for pressing the table yieldingly towards the abutment.

31. In a sheet feeding machine, a supply table, means for feeding a bank thereover, a fixed abutment between which and the rear end of the table the bank is fed, of means for pressing the front end of the table towards the abutment.

32. In a sheet feeding machine, a supply table, means for feeding a bank thereover, a fixed abutment between which and the front end of the table the bank is fed, of means for pressing the front end of the table towards the abutment.

33. In a sheet feeding machine, a supply table, means for feeding a bank thereover, a fixed abutment between which and the rear end of the table the bank is fed, a fixed abutment between which and the front end of the table the bank is fed, of means for pressing the table yieldingly towards the abutments.

34. In a sheet feeding machine, a supply table, means for feeding a bank thereover, a fixed abutment between which and the rear end of the table the bank is fed, a fixed abutment between which and the front end of the table the bank is fed, of independent means for pressing the table towards said abutments, respectively.

35. In a sheet feeding machine, the combination with an upper supply table, means for feeding a bank over said table including a drum and a band thereon, a lower supply table, means for feeding a bank over said table including a band, of means under the influence of gravity for maintaining normally the second named band engaged with that portion of the first named band on the drum.

36. In a sheet feeding machine, the combination with an upper supply table, means for feeding a bank over said table including a drum and a band thereon, a lower supply table, means for feeding a bank over said table including a band, of means for pressing the rear end of the table yieldingly towards the drum.

37. In a sheet feeding machine, the combination with an upper supply table, means for feeding a bank over said table including a drum, located at the rear end of the table and a band thereon, a lower supply table, means for feeding the bank over the lower supply table including a roll, located at the front end of the table, and a band thereon, of mechanism for rotating the drum and roll.

38. In a sheet feeding machine, the combination with a supply table, means for pressing upwardly the supply table yieldingly, a fixed abutment for limiting the upward movement of the rear end of the table, a fixed abutment for limiting the upward movement of the front end of the table, of means for varying the location of

the second named fixed abutment relatively to the front end of the table.

39. In a sheet feeding machine, the combination with a supply table, means for pressing upwardly the supply table yieldingly, a fixed abutment for limiting the upward movement of the rear end of the table, a fixed abutment for limiting the upward movement of the front end of the table, of means for varying the location of the second named fixed abutment vertically relatively to the front end of the table.

40. In a sheet feeding machine, the combination with a supply table, means for pressing upwardly the supply table yieldingly, a fixed abutment for limiting the upward movement of the rear end of the table, a fixed abutment for limiting the upward movement of the front end of the table, of means for varying the location of the second named fixed abutment laterally relatively to the front end of the table.

41. In a sheet feeding machine, the combination with a supply table, means for pressing upwardly the supply table yieldingly, a fixed abutment for limiting the upward movement of the rear end of the table, a fixed abutment for limiting the upward movement of the front end of the table, of means for varying the location of the second named fixed abutment longitudinally relatively to the front end of the table.

42. In a sheet feeding machine, the combination with a supply table, means for pressing upwardly the supply table yieldingly, a fixed abutment for limiting the upward movement of the rear end of the table, a fixed abutment for limiting the upward movement of the front end of the table and means for feeding a bank over the table including a roll located at the front end of the table, of means for controlling the direction in which the roll moves under the depressing influence of the bank passing between the front end of the table and the fixed abutment cooperating therewith.

43. A sheet feeding machine having, in combination, a staking finger for staking all but the top sheet in a pile of sheets adjacent their leading edges, a hold-down for the top sheet, a suction device engaging the exposed face of the top sheet for withdrawing it from beneath the hold-down, and a suction device engaging said exposed sheet for delivering the separated sheet from the pile.

44. A sheet feeding machine having, in combination, a staking finger for staking all but the top sheet in a pile of sheets adjacent their leading edges, a hold-down for the top sheet, a rotary suction device for withdrawing the top sheet from beneath the hold-down, and a rotary suction device for delivering the withdrawn sheet from the pile.

45. In a sheet feeding machine, the combination with a supply table, means for feeding a bank thereover, and a table for receiving the front end of the bank from the supply table, of means for imparting a bend in the bank in the gap between the tables.

46. In a sheet feeding machine, the combination with a supply table, means for feeding a bank thereover, a table in advance of the supply table for receiving the front end of the bank, and means for imparting a bend in the bank in the gap between the tables, of means for varying the extent of the bend.

47. In a sheet feeding machine, the combination with a supply table, means for feeding a bank thereover, and a table in advance of the supply table for receiving the front end of the bank from

the supply table, of a staking finger beneath which the front end of the bank is fed.

48. A sheet feeding machine having, in combination, means for supporting the front end of a bank, means for staking it, means for withdrawing the top sheet in the front end of the bank from beneath the staking means, and means located entirely above the front end of the bank for supporting the staking means.

49. In a sheet feeding machine, the combination with means for supporting the front end of a bank and a hold-down for the top sheet in the front end of the bank, of means located entirely above the front end of the bank for supporting the hold-down.

50. In a sheet feeding machine, the combination with a table for supporting a pile of sheets comprising the front end of a continuous bank, a hold-down for the top sheet in the front end of the bank, mechanism for feeding the front end of the continuous bank beneath the hold-down into position on the table, and a device spaced from the hold-down for withdrawing the top sheet in the front end of the bank from beneath the hold-down, of means, engaging the withdrawn sheet in the space between the device and the hold-down, for elevating the withdrawn sheet bodily from the front end of the bank to a position directly above.

51. In a sheet feeding machine, the combination with a table for supporting a pile of sheets comprising the front end of a continuous bank, a hold-down for the top sheet in the front end of the bank, mechanism for feeding the front end of the continuous bank beneath the hold-down into position on the table, and a device spaced from the hold-down for withdrawing the top sheet in the front end of the bank from beneath the hold-down, of means, engaging the withdrawn sheet in the space between the device and the hold-down, for elevating the withdrawn sheet bodily from the front end of the bank and delivering the sheet in a position reverse to that it occupied on the front end of the bank.

52. In a sheet feeding machine, the combination with a table for supporting a pile of sheets comprising the front end of a continuous bank, a hold-down for the top sheet in the front end of the bank, mechanism for feeding the front end of the continuous bank beneath the hold-down into position on the table, and a device spaced from the hold-down for withdrawing the top sheet in the front end of the bank from beneath the hold-down, of a suction drum, engaging the withdrawn sheet in the space between the device and the hold-down, for elevating the withdrawn sheet bodily from the front end of the bank into a position directly above it.

53. In a sheet feeding machine, the combination with a table for supporting a pile of sheets comprising the front end of a continuous bank, a hold-down for the top sheet in the front end of the bank, mechanism for feeding the front end of the continuous bank beneath the hold-down into position on the table, and a device spaced from the hold-down for withdrawing the top sheet in the front end of the bank from beneath the hold-down, of a suction drum, engaging the withdrawn sheet in the space between the device and the hold-down, for elevating the withdrawn sheet bodily from the front end of the bank and delivering it in a position reverse to that it occupied on the front end of the bank.

54. A sheet feeding machine having, in combination, means for supporting a pile of sheets

- comprising the front end of a continuous bank, means for separating the top sheet from the front end of the bank, and means for picking up the separated sheet, withdrawing the separated sheet from the front end of the bank and delivering it in a reversed position from that it occupied on the front end of the bank.
55. A sheet feeding machine having, in combination, a hold-down engaged with the leading edge of the top sheet in the front end of a bank, a device for withdrawing a sheet from beneath the hold-down, and a device for picking up the withdrawn sheet and delivering it in a reversed position from that it occupied on the front end of the bank.
56. A sheet feeding machine having, in combination, a hold-down engaged with the leading edge of the top sheet in the front end of a bank, a rotary suction device for withdrawing a sheet from beneath the hold-down, and a rotary suction device for picking up the withdrawn sheet and delivering it in a reversed position.
57. In a sheet feeding machine, the combination with an upper supply table and a lower supply table, of bands for feeding a bank over the tables, respectively, said bands forming a reversing throat for the bank during the passage of the bank from the upper supply table to the lower supply table.
58. In a sheet feeding machine, the combination with an upper supply table, a lower supply table, and bands for feeding a bank over the tables, respectively, said bands forming a reversing throat for the bank during the passage of the bank from the upper supply table to the lower supply table, of means permitting one band to move away from the other band to adapt the throat automatically to the thickness of the bank.
59. In a sheet feeding machine, the combination with an upper supply table, a lower supply table, and bands for feeding a bank over the tables, respectively, said bands forming a reversing throat for the bank during the passage of the bank from the upper supply table to the lower supply table, of means for driving the bands differentially.
60. In a sheet feeding machine, the combination with a supply table, means for feeding a bank thereover, a table in advance of the supply table for receiving the front end of the bank and means for imparting a bend in the bank in the gap between the tables, of means for varying the location of the bend.
61. In a sheet feeding machine, the combination with a supply table, means for feeding a bank thereover, a table in advance of the supply table for receiving the front end of the bank, and means for imparting a bend in the bank in the gap between the tables, of means for varying the location and extent of the bend.
62. In a sheet feeding machine, the combination with a suction drum rotating about a fixed axis, for delivering a sheet from a pile, having a circular series of openings on each end face open to the periphery of the drum, and valve disks, each having a passage therein with which the circular series of openings register successively during the rotation of the drum, the passage being extended to communicate with a plurality of the openings simultaneously, said disks being supported independently of the drum on opposite ends of the drum, respectively, of means for pressing each disk against the adjacent end face of the drum.
63. In a sheet feeding machine, the combination with a suction drum rotating about a fixed axis, for delivering a sheet from a pile, having a circular series of openings on each end face open to the periphery of the drum, valve disks, each having a passage therein with which the circular series of openings register successively during the rotation of the drum, the passage being extended to communicate with a plurality of the openings simultaneously, said disks being supported independently of the drum at opposite ends of the drum, respectively, and means for pressing each disk against the adjacent end face of the drum, of means for adjusting the disks about an axis on their supports.
64. In a sheet feeding machine, the combination with a suction drum rotating about a fixed axis for delivering a sheet from a pile having a circular series of openings communicating with the periphery of the drum, and means for withdrawing air from the drum of a single means for covering a portion of the periphery of the drum from side to side thereof.
65. In a sheet feeding machine, the combination with a suction drum rotating about a fixed axis for delivering a sheet from a pile having a circular series of openings communicating with the periphery of the drum, and means for withdrawing air through a plurality of the openings simultaneously, of a single means for covering from side to side of the periphery of the drum most of the said plurality of periphery openings.
66. A sheet feeding machine having, in combination, means for supporting a pile of sheets, means for staking the pile of sheets, means for withdrawing the top sheet in the pile from beneath the staking means, means for holding down the top sheet in the pile, and means for withdrawing the top sheet from beneath the holding-down means.
67. A sheet feeding machine having, in combination, means for supporting a pile of sheets, means for staking the pile of sheets, means for withdrawing the top sheet in the pile from beneath the staking means, means for holding down the top sheet in the pile, means for withdrawing the top sheet from beneath the holding down means, and means located entirely above the pile for supporting the staking and holding down means.
68. In a sheet feeding machine, the combination with means for supporting a pile of sheets, and a rotary suction means, provided with lateral ports, for delivering the sheets one at a time from the pile, of means entirely covering said ports and cooperating therewith for intermittently breaking the suction of said suction means.
69. In a sheet feeding machine, the combination with means for supporting a pile of sheets, a delivering drum, provided with lateral ports, for delivering the sheets one at a time from the pile, and a conduit for conducting atmospheric air from the drum, of means entirely covering said ports and cooperating therewith for intermittently closing the conduit.

CERTIFICATE OF CORRECTION.

Patent No. 1,997,273.

April 9, 1935.

FRED W. BARKLEY.

It is hereby certified that error appears in the printed specification of the above numbered patent requiring correction as follows: Page 5, second column, line 5, for "fornt" read front; page 13, first column, line 67, claim 13, for "or" read of; page 14, second column, line 23, claim 31, for "front" read rear; and page 16, second column, line 25, claim 64, after "drum" insert a comma; and that the said Letters Patent should be read with these corrections therein that the same may conform to the record of the case in the Patent Office.

Signed and sealed this 28th day of May, A. D. 1935.
